LATCHING MECHANISM FOR FILE ROD PULL
AND CABINET CONTAINING SAME
Forest G. Stark, Jamestown, N.Y., assignor to Art Metal,
Inc., Jamestown, N.Y., a corporation of New York
Filed Sept. 22, 1960, Ser. No. 57,758
3 Claims. (Cl. 129—16)

This invention relates to cabinets, particularly filing cabinets. More particularly, this invention relates to filing cabinets containing a file rod running along the bottom of a drawer thereof and a file rod pull attached to the front end of the file rod. Still more particularly, this invention relates to a latching mechanism for a file rod pull.

It is desirable in the manufacture of cabinets, such as filing cabinets and the like, that the finished product presents a neat and attractive appearance. It is also desirable that the front face of such cabinets contains none or a minimum of projections thereon so as to reduce or eliminate the possibility of garments of personnel working around the filing cabinets catching in these projections and causing damage to the garments and/or injury to the personnel.

Filing cabinets usually have therein a file rod for attachment to or use in connection with indexing or filing cards. These file rods are usually attached or fixed to a file rod pull extending outwardly from the front face of the cabinet and the resulting projection is sometimes a source of annoyance and danger to personnel working with the files.

It is an object of this invention to provide a cabinet, such as a filing cabinet, having a neat and clean appearance.

It is another object of this invention to provide a latching mechanism for a file rod pull such that the front face or panel of the cabinet containing the same is unmarred by a projection extending outwardly from the face thereof.

It is another object of this invention to provide a relatively simple and efficient latching mechanism for a file rod pull.

Yet another object of this invention is to provide a cabinet having a centrally positioned, simple, effective latching mechanism for a file rod pull therein and wherein no projections appear on the front face of the cabinet due to the latching mechanism of the file rod pull and/or the file rod pull itself.

Still another object of this invention is to provide a flush type latching mechanism for a file rod pull.

How these and other objects of this invention are achieved will become apparent in the light of the accompanying disclosure and drawings which illustrate one embodiment of this invention and wherein:

FIG. 1 is a front view of a cabinet provided with a latching mechanism for a file rod pull in accordance with this invention;

FIG. 2 is a partial side elevation view of the cabinet of FIG. 1;

FIG. 3 is an enlarged, partial cross sectional view taken along line III—III of FIG. 1;

FIG. 4 is an enlarged partial cross sectional view taken along line IV—IV of FIG. 1; and

FIG. 5 is a back view of the latching mechanism of this invention illustrated in FIGS. 3 and 4.

In accordance with this invention there is provided a latching mechanism for a file rod pull particularly useful in a cabinet having a drawer provided with a file rod, wherein the file rod pull is flush with the front or front face of the cabinet drawer and cabinet. More particularly, in accordance with this invention there is provided a latching mechanism for a file rod pull capable of being installed in a cabinet and flushly mounted with respect to the front face thereof. The complete assembly comprises a file rod fixed to the back of a file rod pull, said pull being mounted

2

and disposed with respect to said cabinet, particularly the front face of the drawer provided with a file rod and file rod pull therefor, such that the front of the file rod pull when the file rod pull is in latched position, is substantially flush with the front face of the drawer or cabinet within which the file rod pull is mounted. Means are also provided in accordance with this invention for releasably holding said file rod pull in latched position with respect to the cabinet and the drawer thereof within which the file rod pull is mounted so that the front of said file rod pull is maintained in a position flush with respect to the front of said drawer and cabinet. Means are also provided in accordance with this invention associated with said file rod pull to urge said file rod pull into engagement with said holding means to better maintain said file rod pull in the latched position.

Referring now to the drawings which illustrate an embodiment of this invention, there is illustrated a cabinet drawer generally indicated by reference numeral 1, the cabinet drawer being provided with mountings 2a and 2b. One of the mountings, such as mounting 2a is adapted for the insertion and holding of a drawer identification card therein and the other of said mountings, such as mounting 2b, serves to outline a recessed portion in drawer front 4 for grasping in order to pull out drawer 1 from the cabinet or frame within which it is mounted.

Cabinet drawer 1 comprises side walls 3 and cabinet or drawer front 4 made up of a front wall 4a and a rear wall 4b. Recess 5 is provided in the cabinet front 4 through front wall 4a within which is located file rod pull 6, the front 6a of file rod pull 6 being substantially flush with front wall 4a of cabinet front 4. File rod 7 is fixed at its front end by suitable means such as by being threadedly engaged into the back 6b of file rod pull 6, the back end of file rod 7 being inserted in holder-guide 8 mounted on the rear wall 9 of drawer 1.

As illustrated, top 6c of file rod pull 6 is provided with an indentation or groove 6d extending transversely thereof across the full width of file rod pull 6. The bottom 6e of file rod pull 6 is curved downwardly and inwardly from the back 6b to the front 6a so that the front portion of file rod pull 6 is thicker than the rear portion. The bottom edge of front wall 4a of drawer front 4 at the top of recess 5 therein is provided with an inwardly and downwardly depending flange 10 which is adapted to be releasably engaged in groove 6d of file rod pull 6 when the file rod pull 6 is in the latched position illustrated in the drawings.

Biassing means are also provided and associated with the latching mechanism assembly of this invention to maintain file rod pull 6 in the latched position. The biassing means comprises elongated bar or wire 11 carried between its crimped ends 11a within suitable openings provided within flanges or tab portions 12a of intermediate wall 12 of drawer front 4 located intermediate front wall 4a and rear wall 4b thereof. As illustrated in the drawings, see particularly FIGS. 3—5, rear wall 4b is cut out to provide a substantial opening within which file rod pull 6 and file rod 7 are centrally located at about the bottom of drawer 1. It is thus seen that bar 11 when in contact with bottom surface 6e of file rod pull 6 tends to urge file rod pull 6 upwardly as illustrated in the drawings so as to better maintain releasable holding means or flange 10 engaged or fitted within groove 6d across the top 6c of file rod pull 6.

In the operation of the file rod latching device of this invention, when it is desired to remove file rod 7 from drawer 1, drawer 1 is withdrawn from its surrounding cabinet or frame by reaching within the recessed portion 2b of drawer front 4 and drawing drawer 1 outwardly for a sufficient distance to expose the bottom 6e of file rod pull 6 is then grasped and file pull 6 withdrawn out of

recess 5. As file rod pull 6 is withdrawn outwardly from within recess 5 releasable holding means or flange 10 is moved out of groove 6d at the top 6c of file rod pull 6. As file rod pull 6 is so moved it carries with it file rod 7.

After a suitable adjustment has been made in the file cards or index cards associated with file rod 7, file rod pull 6 together with file rod 7 is reinserted into drawer 1. As file rod pull 6 is pushed back into recess 5 in the direction so that the rear end of file rod 7 tends to enter holder 8 mounted on the rear wall of drawer 1, bar 11 comes into contact with the bottom surface 6e of file rod pull 6. Upon further movement of file rod pull 6 within recess 5 bar 11 in contact with curved bottom surface 6e of file rod pull 6 tends to urge file rod pull 6 upwardly within recess 5. At the same time as file rod pull 6 moves into recess 5, flange 10 rides along the top 6c of file rod pull 6 until it comes into engagement with groove 6d. When flange 10 enters groove 6d in top 6c of file rod pull 6, file rod pull 6 is in latched position, front 6a of file rod 6 being substantially flush with front wall 4a of drawer front 4. File rod pull 6 is maintained in latched position under the urging of bar 11 which presses upwardly against bottom surface 6e of file rod pull 6 to better maintain flange 10 in engagement within groove 6d.

It is thus seen that there is provided in accordance with this invention a simple, effective file rod pull and latching mechanism therefore particularly suitable for use in a cabinet provided with a drawer containing a file rod, the file rod pull and latching mechanism therefore being adapted so as not to present any outward projection on the front surface of a cabinet or drawer containing the same.

As will be apparent to those skilled in the art in the light of the accompanying disclosure many modifications, changes, alterations and substitutions are possible in the practice of this invention without departing from the spirit or scope thereof.

I claim:

1. A filing drawer comprising a drawer front having a front wall and a rear wall, said rear wall of said drawer front being spaced from said front wall, said front wall being provided with a centrally located recess at the bottom thereof and extending to the bottom edge, a file rod pull, a file rod fixed to the back of said pull, said file rod pull being fitted within said recess and between said front wall and said rear wall, the front of said file rod

pull being substantially flat, said drawer front being substantially flush with said flat front of said file rod pull and the bottom edge of said pull being substantially in line with the bottom edge of said front wall, said file rod 5 extending through an opening in said rear wall, said file rod pull being provided with gripping means comprising a bottom surface extending substantially horizontally from the back of said pull toward the front of said pull and then extending downwardly to the bottom edge of said pull so that the upper portion of said pull is thicker than the lower portion of said pull, the top of said pull being provided with an indentation therein, releasable holding means on said drawer front wall releasably fitted in said indentation and biasing means in said drawer 10 front adapted to contact the substantially horizontal portion of the bottom surface of said pull to urge said pull upwardly to retain said releasable holding means fitted in said indentation, said downwardly extending surface portion of said gripping means extending below said biasing 15 means and adapted to be engaged by a finger to withdraw 20 said file rod pull from said recess.

2. A filing drawer in accordance with claim 1 wherein said releasable holding means is an inwardly and downwardly depending flange portion of said front wall of 25 said drawer front.

3. A filing drawer in accordance with claim 1 wherein said releasable holding means is an inwardly and downwardly depending flange portion of said front wall of said drawer front and wherein said biasing means is an 30 elongated element extending transversely with respect to the bottom surface of said file rod pull and positioned intermediate said front wall and said rear wall of said drawer front.
